SLIP BOWL

Benjamin F. Kelley, Tulsa, Okla., assignor to Ben F. Kelley Co., Inc., a corporation of Oklahoma
Filed Dec. 4, 1961, Ser. No. 156,605
6 Claims. (Cl. 24—263)

This invention relates to improvements in slip bowls.

Slip bowls are commonly used in well drilling to form seats for pipe-gripping slips which are employed to grip pipe strings as the latter are inserted into and removed from well bores during the course of drilling wells and while running pipe for equipping wells.

Such slip bowls will commonly have a downwardly tapering conical bore through which the pipe is run to provide a seat surface for wedging the slips into gripping engagement with the pipe.

In oil well drilling operations, drill pipe, which is run through the bowl, will ordinarily be made up of sections connected together by tool joints or other couplings which form enlargements about the surface of the pipe. Tool joints are frequently made of metal which is harder than the metal of the slip bowl. As a result, in the course of running the pipe through the bowl, the surfaces of the bowl, particularly at the throat or smaller diameter region of the conical bore, will become badly worn so that the slips will be deprived of full bearing surface on the slip bowl, thereby making their grip upon the pipe uncertain and frequently hazardous. This is particularly true in the case of the so-called "automatic" or power slips by which the slips are raised and lowered relative to the slip bowl by power means during gripping and releasing of the pipe.

It is, therefore, a primary object of the present invention to provide an improved slip bowl construction which will obviate the difficulties such as are enumerated above, which are encountered in the use of more conventional slip bowls.

A further object is to provide a slip bowl having a removable wear ring or guide bushing positioned at the throat of the bowl where the greatest degree of wear is normally encountered.

A further object is to provide a slip bowl employing a removable hard metal wear ring or guide bushing in the throat of the bowl and a split retainer ring for holding the bushing in place but which may be removed for replacement of the bushing as the latter becomes worn in service.

Other and more specific objects of this invention will become more readily apparent from the following detailed description when read in conjunction with the accompanying drawing which illustrates a useful embodiment in accordance with this invention.

In the drawing:

FIG. 1 is a vertical cross-sectional view of a slip bowl constructed in accordance with this invention;

FIG. 2 is a transverse cross-sectional view looking upwardly along line 2—2 of FIG. 1; and

FIG. 3 is a fragmentary view, in perspective, illustrating a detail of the invention.

As shown in the drawing, the slip bowl, designated generally by the letter B, is shown in the position commonly occupied in a conventional master bushing M seated in the usual rotary table R of a rotary well drilling rig. The rotary table and master bushing form no part of the present invention and are shown in broken lines merely for purposes of illustration of a conventional support for the slip bowl.

Slip bowl B may be of any suitable so-called "solid" type, that is, a continuous structure as compared with split types which are also commonly used in the well drilling industry. Bowls of the solid type are commonly used

2

with power slips and often in running casing as well as other types of pipe strings. As shown in the illustrative embodiment, slip bowl B comprises a body 10 which is provided about its upper end with an annular flange F which is adapted to rest on the top surface of master bushing M. Also, the exterior of slip bowl B is provided immediately below flange F with a portion 12 of square or other non-round shape to seat non-rotatably in a corresponding opening in master bushing M. The remainder 10 of the exterior surface of the slip bowl extending below portion 12 will ordinarily have a generally conical inwardly tapering shape, indicated at 13, for seating in a correspondingly shaped seat provided in master bushing M.

Body 10 of the slip bowl has an axial bore comprising a main bowl portion 14 of downwardly and inwardly tapering, generally conical shape merging into a throat portion 15. The latter merges with a downwardly and outwardly flaring bore portion 17, also of generally conical form. In the region of throat portion 15, the bore wall of the slip bowl is provided with an annular recess 18 coaxial with the bore of the bowl and generally cylindrical in shape. The upper end of the recess is defined by the downwardly facing shoulder 16. The lower end of recess 18 is enlarged diametrically for a short distance to form a relatively narrow annular groove 19 in the wall of the bowl, terminating just above the lower end of the bowl.

Seated in recess 18 is a wear ring or guide bushing 20 which will be constructed of relatively hard metal or metal which has been treated to provide a hard external surface, the metal or hardened surface being harder than the metal from which the bowl is constructed. The bore of bushing 20 will be coaxial with that of the slip bowl and the inner periphery of bushing 20 is shaped to define the throat portion of the bowl. The upper portion of the bore of bushing 20 is provided with downwardly and inwardly tapering surface 21 forming a continuation of the surface of bowl portion 14 and leading into a short cylindrical portion 21a. The portion 21b of the bore of bushing 20 below cylindrical portion 21a, tapers downwardly and outwardly to conform to the slope of portion 17 of the bore of the slip bowl. A split retainer ring, designated generally by the numeral 22, is seated in groove 19 and comprises at least four complementary arcuate segments, one of which may be designated the key segment 22a and is preferably made considerably shorter than the other three segments, designated 22b, 22c, and 22d. Key segment 22a is provided with a radially outwardly projecting stud or rivet 24 which is adapted to project through a

registering hole 25 extending from the bottom of groove 19 through the wall of the slip bowl. The outer end of rivet 24, when the ring is in place, will project through hole 25 and may be peened or otherwise riveted to secure it in place in hole 25, thereby securing the retainer ring 22 below bushing 20 in retaining relation to the lower end thereof. The upper end of bushing 20 will be held against upward displacement by engagement with shoulder 16. The inner periphery of retainer ring 22 is formed with a conical taper 26 diverging downwardly to conform with the taper of portion 17 of the slip bowl and portion 21b of the bushing.

Bushing 20 will be made to have a sliding fit in recess 18 so that while it cannot be displaced from the recess, it is free to rotate in the recess. This is quite important because, as pipe is run through the slip bowl, the ability of the bushing to rotate freely will reduce the possibility of excessive wear on the bushing at any particular point, and thus will tend to assure uniformity of wear over the entire surface of the bushing.

Whenever the wear of the bushing does become excessive, the retainer ring can be removed by cutting off the expanded or riveted portion of stud 24 and knocking seg-

ment 22a out of groove 19, thereby allowing the other segments of the ring to be removed. Thereupon, bushing 20 can be slipped out of recess 18 and a new bushing substituted therefor and then locked in place by a new retainer ring.

By means of the construction previously described, it will be seen that the life of slip bowls can be greatly extended by the use of a hardened replaceable guide bushing which is positioned in the region of the bowl in which excessive wear occurs.

It will be understood that various changes and alterations may be made in the details of the illustrative embodiment within the scope of the appended claims but without departing from the spirit of this invention.

What I claim and desire to secure by Letters Patent is:

1. A slip bowl, comprising, a generally tubular metal body having a generally conical bore tapering downwardly and inwardly from its upper end, an annular guide bushing rotatably seated wholly within the wall of said bore above its lower end to define the throat portion of said bore, said bushing being constructed of metal harder than said body, and a split retainer ring seated in the bore wall of said body beneath the lower end of said bushing to secure the latter in place in said bore wall.

2. A slip bowl according to claim 1 wherein said retainer ring comprises a plurality of complementary arcuate segments, and wherein there are means carried by at least one of said segments for fixedly securing the same to said body.

3. A slip bowl according to claim 1 wherein said retaining ring comprises a plurality of complementary arcuate segments, and wherein there is a rivet member projecting radially outwardly from one of said segments receivable in a registering hole in said body for fixedly securing the same to said body.

4. A slip bowl, comprising, a generally tubular metal body having a thorough bore including a generally conical bore portion tapering downwardly and inwardly from its upper end, a coaxial annular recess in the wall of said bore above its lower end, an annular groove in the wall 40 of said bore communicating with the lower end of said

recess and larger in diameter than the latter, an annular guide bushing rotatably seated wholly within said recess, the bore of said bushing defining the throat portion of said bowl, said bushing being constructed of metal harder than said body, and a split retainer ring seated in said groove in retaining relation to the lower end of said guide bushing.

5. A slip bowl according to claim 4 wherein said retainer ring comprises a plurality of complementary arcuate segments, and wherein there are means carried by at least one of said segments for fixedly securing the same to said body.

6. A slip bowl, comprising, a generally tubular metal body having a through bore comprising a generally conical first bore portion tapering downwardly and inwardly from its upper end merging with a generally conical second bore portion tapering downwardly and outwardly to the lower end of the body, a coaxial annular recess in wall of said bore at the juncture of said bore portions, an annular guide bushing constructed of metal relatively harder than said body rotatably seated wholly within said recess, the upper and lower end portions of the bore wall of said bushing having tapers respectively forming portions of said first and second bore portions and defining the throat portion of the slip bowl, and a split retainer ring seated in the wall of said second bore portion in retaining relation to the lower end of said guide bushing, the inner wall of said retainer ring having a taper corresponding substantially to that of said second bore portion, said retainer ring comprising a plurality of complementary arcuate segments, and means carried by at least one of said segments for fixedly securing the same to said body.
